Inventor:
John Perham

United States Patent Office.

JOHN PERHAM, OF ROCKTON, ILLINOIS.

Letters Patent No. 80,210, dated July 21, 1868.

EXTENSION STOVE-PIPE SHELF.

The Schedule referred to in these Letters Patent and making part of the same.

TO ALL WHOM IT MAY CONCERN:

Be it known that I, JOHN PERHAM, of Rockton, Winnebago county, State of Illinois, have invented certain new and useful Improvements in Stove-Pipe Shelves; and I do hereby declare the following description and accompanying drawings are sufficient to enable any person skilled in the art or science to which it most nearly appertains to make and use my said invention or improvements without further invention or experiment.

The nature of my invention and improvements consists in providing and constructing an improved metallic stove-pipe shelf, of a peculiar shape or style, being open at one side, attached to a double adjustable collar, and moving loosely thereon by means of slides, slots, or grooves, so that the shelf may be extended or elongated on one side of the stove-pipe by means of drawing out the shelf on the slides in question till the stops *o o* engage with the outside of the collar part *B B C c*. The shelf may also, in this manner, be entirely removed from the pipe, by removing the stops *o o* and drawing the shelf out through the said grooves.

Figure 1 is a perspective view of the shelf *A A* and collar *B B C c* complete.

Figure 2 is a similar view of the collar *B B C c* detached.

Figure 3 are views of detached sections through *m m*, exhibiting the manner of working the slides *A A* of the shelf, in or through the collar *B B C c*, fig. 2.

A A represent the shelf, *B B C c* the collar, and *D D* are bolts and nuts or screws for adjusting and holding the collar in position on the pipe of the stove.

Similar letters of reference indicate like parts.

What I claim as my invention, and desire to secure by Letters Patent, is—

1. An improved metallic extension stove-pipe shelf, *A A*, constructed and arranged with the extension-device, as shown, made in one or more parts, to operate substantially as described.
2. An improved metallic stove-pipe shelf, provided with and operating by means of grooved or sliding ways, to allow of an extension of the size of the shelf by elongation or lateral enlargement.
3. The peculiar-shaped adjustable grooved or slotted collar *B B C c*, in two parts, when constructed and arranged to operate substantially as set forth, for the purpose described.
4. In combination with the foregoing, the screws or bolts and nuts *D D*, and radial arms and circular ribs, substantially as shown, with guard-stops *o o* of the shelf *A A*, when the whole is constructed and arranged substantially as herein set forth and described, to operate as specified.

JOHN PERHAM.
